(57) **CLAIM**

The ornamental design for a light housing, as shown and described.

DESCRIPTION

FIG. 1 is a top perspective view of a light housing showing my new design;

FIG. 2 is a bottom perspective view thereof;

FIG. 3 is a right side elevation view, the left, front and rear views being a mirror image;

FIG. 4 is a top plan view thereof; and,

FIG. 5 is a bottom plan view thereof.

The broken lines in the drawings are included for the purpose of illustrating unclaimed portions of the light housing and form no part of the claimed design.

1 Claim, 5 Drawing Sheets
